INCINERATOR

John H. Tarment, Foxboro, Mass.

Application December 11, 1936, Serial No. 115,387

6 Claims. (Cl. 110—18)

The essential object of the invention is to provide an incinerator in which waste material may be burned at all times with safety.

A further object of the invention is to provide an incinerator in which the material to be burned may conveniently be stirred to facilitate combustion; and, also, to provide an incinerator from which the ash may be easily removed.

The invention can best be seen and understood by reference to the drawings, in which

Fig. 1 is a perspective of the incinerator.

Fig. 2 is a front elevation with the incinerator in open inoperative position for cleaning the grate.

Fig. 3 is a vertical section of a portion of the incinerator; and

Fig. 4 is a plan taken on the line 4—4 of Fig. 3.

Referring to the drawings 1 represents the body of the incinerator. This body is made of sheet metal, cylindrical in form, and imperforate. The body is provided with handles 2 by which it may be lifted.

3 represents the bottom of the incinerator, or grate. The grate is made of sheet metal. It is circular in form, preferably slightly dished, and is a little larger than the bottom of the body 1 which is left open, the grate forming the bottom to the body, though separate from it. The grate is perforated with openings 4, through which air may enter for purposes of combustion.

Both the body of the incinerator and the grate are set within a skeleton frame, or holder, 5, which functions, also, as a base support. This holder is composed of strips of sheet metal.

Of these 6 represents vertical spaced strips circularly arranged to assist in the formation of the frame which embraces the lower portion of the incinerator body. Encircling these strips, and riveted to them, are spaced hoops, or bands,

1. Certain of the strips 6 of those oppositely arranged are extended downwardly below the bottom hoop 7 of the holder and bent upon themselves to provide legs 9 which support the holder,

and thence are bent to provide sections 10 which extend horizontally and diametrically, crossing one another to form the open bottom of the holder, the strip sections 10 being riveted to one another at the point of their crossing. With

their ends fitting within those turned portions of the strips which form the legs 9 of the holder, and rising upwardly therefrom, are bent pieces 12, bent to provide lifts, or supports, 13 on which the grate, fitting loosely within the holder, rests.

After providing the lifts, or supports, for the

grate the pieces 12 are bent down and riveted to the sections 10 of the strips.

The grate resting upon the lifts 13, and fitting loosely within the holder, is a movable grate and, accordingly, may be shaken, for which purpose the grate is provided with a shaker 15. This shaker is riveted to the under side of the grate and its shank projects laterally between a set of the spaced bars 6 of the holder, and is fitted with a handle 15. The shaker is movable through the arc lying between the spaced strips 6 between which the shank of the shaker is extending. The arrangement is, also, preferably such that during the shaking the shank of the shaker may move over the top edge of the lower band 7 over which the shank is projecting, the rising of the lifts 13 which support the grate being such as will locate the grate in position slightly above the top edge of the lower hoop 7 on the holder so as to permit the shank of 20 the shaker resting on the hoop during the shaking.

The body 1 of the incinerator may rest upon the grate but, if resting upon the grate the body will be moved during the shaking and this is avoided by providing a separate support for the body. To this end the vertical strips 6 of the holder are provided on the inside with a circular band, or hoop 16 riveted thereto. Encircling the lower end of the body 1 is a band, or hoop 17, 30 riveted thereto. The band, or hoop 17, on the body is so located with relation to the hoop 16 on the holder that when the body is lowered into the holder the band 17 on the body will engage the band 16 on the holder, and the body will be supported from off the shoulder on the holder thus provided. When thus supported the bottom end of the body will just clear the grate and permit of the grate being moved without moving the body. The grate is preferably provided with an upturned flange 18 around its peripheral edge which overlaps the bottom edge of the body 1 when resting in the holder in order to form at this point a relatively tight joint. The grate is, also, provided with angle pieces 19 fixed to the top surface thereof which act as stirrers for the material being burned when the grate is shaken or moved.

The body 1 of the incinerator is provided with a cover 20 having a flanged edge 21 which laps 50 by the top of the body when the cover is closed. The cover is preferably a hinged cover, hinged to the body by hinge connection 22. On the side of the cover opposite its hinged connection is a handle 23 for opening the cover. The hinged 55

connection 22 is provided with a stop 25 which engages the cover when the cover has been moved to a full open position, and will maintain the cover in this open position until turned down and closed. The cover is preferably made generally convex and is provided with a relatively large central opening 26. This opening is covered by a wire mesh 27 which rises from around the edge of the opening, and thence extends upwardly from the cover in the form of a cone. Mounted on the top of the conical wire mesh 27 is a guard 28. This guard is concaved, is separated from the opening in the cover by the conical wire mesh, and is preferably slightly larger than the opening 26 in the cover. The conical wire mesh is secured to the cover and reinforced by metal straps 29 riveted to the cover and crossing one another in the apex of the screen. The guard 28 is secured to these straps at the point where they cross by means of a bolt and nut connection 30.

The general operation is as follows: Assuming the body of the incinerator which forms the combustion chamber to be set within the holder and the cover closed, combustion of material within the incinerator will be carried on with practically absolute safety under all conditions. The flame will be confined to the incinerator and will not even lap through the screened opening in the cover. There will be little or no escape of sparks and should any sparks pass through the mesh they will strike the guard and be deflected back onto the cover. Air will be admitted for purposes of combustion through the openings in the grate although more or less air will enter around the edge of the grate between it and the bottom edge of the incinerator body. To facilitate combustion within the incinerator in case it becomes lousy the grate may be shaken, at which time the angle pieces on the grate will act as stirrers to the material being burned. After the combustion has been completed the body may be lifted out of the holder and the ash on the grate then swept away or allowed to be removed by the wind. In fact, it is not necessary to remove the body of the incinerator from the holder for clearing the grate. The body only need be lifted sufficiently to provide access to the grate for cleaning it, or for the wind to blow the ash away. For holding the body when lifted the top band 7 of the holder has pivoted to it a hook 31 having a handle 32. The normal gravitated position of this hook is one in which the hook will lie within the plane of the body. Accordingly, when the body is in place in the holder the hook will bear against the side of the body. When, however, the body has been raised in the holder to a point where the bottom edge of the body will lie above the hook, then the hook will move forward into the plane of the body beneath its bottom edge and on again lowering the body into the holder the hook will hold the body in an elevated position where it may be left for clearing of the grate. When it is again desired to use the incinerator the hook is released by upward pull upon its handle, when the body will fall back into place and the incinerator will be ready for use.

I claim:

1. In an incinerator the combination comprising a body forming a combustion chamber and having an open bottom end, a holder for said body in which said body may be lifted, a grate mounted within said holder, and with which the open bottom end of said body has substantially

closed connection when the body is in operative position within said holder, and releasable means borne by said holder for maintaining said body in a raised position in the holder with relation to said grate whereby access will be obtained for cleaning said grate. 5

2. In an incinerator the combination comprising a body forming a combustion chamber and having an open bottom end, a holder for said body in which said body may be lifted, a grate mounted within said holder, means for mounting the grate within the holder whereby the grate may be shaken, means for mounting said body within the holder whereby the open bottom end of said body will lie in conjunctive relation to 15 said grate but separated therefrom when the body is in operative position, and releasable means borne by said holder for maintaining said body in a raised position in the holder with relation to said grate whereby access will be 20 obtained for cleaning said grate.

3. In an incinerator the combination comprising a cylindrical imperforate body of sheet metal open at both ends and forming a combustion chamber, a skeleton frame forming holder 25 for said body made of strips of sheet metal and within which the lower portion of said body is adapted to be contained and out of which said body may be lifted, means forming an elevated stand for said holder, a grate located within the 30 bottom of said holder and with which the open bottom end of said body has substantially closed connection, means for supporting said body, means providing a mounting for said grate, a cover to the open top end of said body, said cover 35 having an opening in it, a conical upwardly projecting screen covering said opening in the cover, a spark arresting guard covering said screen, and means for supporting said guard from off said cover. 40

4. In an incinerator the combination comprising a cylindrical imperforate body of sheet metal having an open bottom end and forming a combustion chamber, a skeleton frame forming holder for said body within which the lower portion 45 of said body is adapted to be contained and out of which said body may be lifted, means providing an elevated stand for said holder, a grate located within the bottom of said holder, means for mounting said grate, and means for mounting said body within and from off said holder whereby the open bottom end of said body will lie adjacent said grate but separated therefrom.

5. In an incinerator the combination comprising a cylindrical imperforate body of sheet metal 55 having an open bottom end and forming a combustion chamber, a skeleton frame forming holder for said body within which the lower portion of said body is adapted to be contained and out of which said body may be lifted, means providing an elevated stand for said holder, a grate located within the bottom of said holder, means for mounting said grate, and hoops on said body and holder, respectively, co-operating with one another when said body is contained within said 60 holder to support said body from off said holder whereby the open bottom end of said body will lie adjacent said grate but separated therefrom. 65

6. In an incinerator the combination comprising a cylindrical imperforate body of sheet metal 70 having an open bottom end and forming a combustion chamber, a skeleton frame forming holder for said body within which the lower portion of said body is adapted to be contained and out of which said body may be lifted, said 75

holder comprising in part spaced vertical strips of sheet metal opposing ones of which are extended to form feet to said holder, thence bent to cross one another at the bottom of said holder, a grate located within the bottom of said holder above said crossed strips, means for mounting

said grate from off said leg forming strips, and means for mounting said body within and from off said holder whereby the open bottom end of said body will lie adjacent said grate but separated therefrom.

JOHN H. TARMENT.
